CONTINUOUSLY OPERATED VERTICAL
CHAMBER OVEN FOR THE PRODUCTION
OF GAS AND COKEPaul Souliary, Bruay, France, assignor, by mesne
assignments, to Koppers Company, Pittsburgh,
Pa., a corporation of DelawareApplication September 19, 1938, Serial No. 230,679
In Germany September 20, 1937

2 Claims. (Cl. 202—251)

The present invention relates to continuously operated vertical chamber ovens for the production of gas and coke and more particularly to that type of vertical chamber ovens in which a special pipe like member is arranged in the chamber roof, said member serving for introducing the coal to be treated into the coking chamber. The said coal delivery pipe reaches down to a zone of the chamber walls near the heating flue system and the distillation gases produced are discharged through an ascension pipe connected to the coking chamber at one of the front sides thereof.

The use of a special coal delivery pipe projecting into the hot zone of the chamber (for instance Austrian patent specification No. 108,700) results in an advantageous and quick carbonization of the coal entering the chamber, at least in the outer layers of the chamber charge, and so prevents the coal from sticking or adhering to the chamber walls.

In practice, however, certain difficulties have arisen in that at the outer walls of the delivery pipe cooled from inside by the freshly charged cold coal, tarry constituents tend to precipitate from the distillation gases which flow round the delivery pipe before they enter the ascension pipe extending from the roof of the chamber. In order to keep the gas paths free from blockages caused by such deposits, the gas space around the delivery pipe must be cleaned manually and for this reason it has been usual to provide an upper cover or roof of the chamber, said cover consisting of removable metal sheets or similar means.

That sort of cleaning work in many cases does not seem to cause any appreciable trouble to the supervisors of the plant. I have found, however, that in the practical operation of a gasworks or the like there may be certain circumstances which render it necessary to repeat said cleaning work at short intervals so that the attendance to the ovens is thereby made very expensive. This may for instance be the case if the working temperature in the chamber is kept low for the production of an easily combustible coke.

Moreover, the distillation gases entering the comparatively cold gas space around the coal delivery pipe are not, in such instances subjected to the heat treatment temperature necessary for the conversion of aliphatic hydrocarbons into the more valuable aromatic constituents. It is known, that the tar obtained from the ordinary continuously operated vertical chamber ovens mostly contains considerably less aromatic con-

stituents than the usual coke oven tar which is produced during the carbonization of coal in horizontal chamber ovens.

The main object of my present invention is to provide such improvements in said vertical chamber or retort ovens for the production of gas and coke which will facilitate the operation of said ovens and will overcome many difficulties caused by the depositing of tarry matter or the like in the upper part of the chamber or retort.

Now, my present invention consists in closing the top of the coking chamber of a continuously operated vertical chamber oven by a massive roof made out of refractory brick work and I provide in said massive roof a coal delivery pipe reaching in the usual way down to near the heated zone of the chamber walls and I further provide within the range of the lower end of the coal delivery pipe that is near to the chamber roof, horizontal channels which are situated in the hot zone of the chamber brick work and which connect with one another the two free spaces which are formed below the chamber roof on the opposite front sides of the coal delivery pipe.

The new design of the chamber roof according to my invention, and of the chamber top, respectively, offers the advantage that all the gas leading spaces, including the channels or spaces leading around the cool coal delivery pipe, are arranged so near to the heating system of the chamber that the temperature of all the spaces remains above the dew point of the gases for tarry constituents. The danger of precipitating tarry constituents in said gas spaces and the blocking up the gas ways thereby, is thereby considerably reduced and in practice an unimportant cleaning work similar to that needed for the usual coke ovens has only to be carried out.

Another important feature of my present invention consists in that the coal delivery pipe in the chamber roof is arranged so as to be withdrawn in such a manner that the lower end of the coal delivery pipe may be put back into the chamber roof. This provision offers the advantage that the metallic delivery pipe can be protected against any dangerous heating up during the usual degraphitisation of the chamber.

Still further objects and features of my present invention may be taken from the following description of a preferred embodiment thereof and from the accompanying drawings in which:

Fig. 1 is a vertical longitudinal section and
Fig. 2 is a vertical cross section through the

upper part of a vertical chamber oven constructed according to my present invention.

Fig. 3 is a view similar to Fig. 2, but illustrating schematically an alternative embodiment of the invention.

On the drawings, the coking chamber is marked 1 which is formed by the refractory brickwork 2 and the side heating walls 3 in which are provided the usual vertical heating flues 4.

The top of the chamber is closed by a massive roof 5 consisting of refractory brickwork. Cleaning holes are provided in the roof, one being at the front side 6 of the chamber which is also used for the gas outlet to the opposite ascension pipe 8 leading to the hydraulic main 7, and the other 9, being at front side of the chamber.

In the centre of the chamber roof 5 there is an opening which is traversed by the coal delivery pipe 10 preferably outer-lined with a heat insulation layer 11.

Around the lower end of the coal delivery pipe 10 in the chamber roof, channels 12 are recessed in the roof 5 which connect the left hand gas collecting space a with the right hand gas collecting space b, as shown in Fig. 1, and which are formed above the coal charge in the chamber.

As may be seen from Fig. 1, the upper extremities of the gas collecting spaces A, B and the lower extremity of both the circulating channels 12 and pipe 10 are situated near the heating flues 4 and terminate at about the level of but not below the tops of the horizontal channel 13 connecting the heating flues 4 so that the temperature in these gas leading spaces is always kept so high that the tarry constituents may not condense.

The gas circulating channels 12 are equipped with closable cleaning holes 14 so that they can easily be cleaned from above the chamber roof.

The coal delivery pipe 10 is arranged in the chamber roof in such a manner that it can be withdrawn. The outlet branch 15 of the coal bunker 16 projects like a telescope into the delivery pipe 10 so that the latter may be drawn upwards vertically over the branch 15.

The coal delivery pipe is suitably withdrawn before the chamber is decarbonised so as to protect the lower end of the pipe 10 against an excessive heating up.

Openings 17 which can be shut are provided in the delivery pipe in order to supervise and accelerate the passage of the coal, if necessary. Between the delivery pipe 10 and the chamber roof, on the one hand, and the bunker outlet 15, on the other hand, there are the usual packing means for instance sand seals and stuffing boxes respectively.

Instead of carrying out the chamber as illustrated in Fig. 1, the chamber can also be equipped with a multitude of coal delivery pipes as diagrammatically illustrated in Fig. 3, within the range of which gas circulating channels 12 may likewise be provided so that constantly all the gas collecting spaces are connected with the ascension pipe by means of the gas channels lying in the hot zone.

According to the present invention, the coal delivery pipes of adjacent oven chambers also may be connected with a common bunker outlet. In this case, the coal delivery pipes extend slantingly toward the chamber and the bunker outlet is arranged above the heating walls so that the two streams of coal in passing from the bunker outlet to the two chambers connected therewith have to take the same path way.

Fig. 2 shows that the gas circulating channels 12 partly project into the chamber side walls. Instead of this it is also possible to carry out the invention with the coal delivery pipe 10 so narrow that the channels 12 are within the range of the chamber walls. It is of utmost importance for the present invention that the hollow spaces of the oven which carry the distillation gas be situated near the heating system of the chamber, so that in all the gas spaces there always exists a comparatively high temperature which, on the one hand prevents the aforesaid condensation, and on the other hand effects the desired conversion of alipathic constituents into those of the aromatic series.

I have now above described my present invention on the lines of a preferred embodiment thereof, but my invention is not limited in all its aspects to the mode of carrying it out as described and shown, since the invention may be variously embodied within the scope of the following claims.

I claim:

1. In a continuous vertical coking retort oven comprising a vertical coking chamber intermediate heating walls on opposite sides thereof, and a heating flue system in the heating walls extending to near but terminating at its upper part at a short distance below the tops of the heating walls and coking chamber; the combination of a massive roof of refractory brickwork covering the top of the chamber and extending down into the chamber top, from one end to the other thereof between the tops of the heating walls with its base terminating at the level of the upper extremity of the heating flue system, an ascension pipe opening extending through one end of the roof, a metallic coal-delivery pipe extending down through the center of the roof and also terminating at its lower end at the level of the upper extremity of the heating flue systems, and a recessed channel formed in the bottom of the roof, said channel being recessed from the base of the roof upwardly and inwardly from the two ends of the roof so as to surround the delivery pipe to allow the gas collected in the collecting space to pass over and above the coal pile formed from the delivery pipe to the ascension pipe opening, but being shallow relative to the depth of the massive roof to confine the passing gas closely to the tops of the heating systems and thus prevent undue cooling and condensation of the gas so passing.

2. In a continuous vertical coking retort oven comprising a vertical coking chamber intermediate heating walls on opposite sides thereof, and a heating flue system in the heating walls extending to near but terminating at its upper part at a short distance below the tops of the heating walls and coking chamber; the combination of a massive roof of refractory brickwork covering the top of the chamber and extending down into the chamber top, from one end to the other thereof between the tops of the heating walls with its base terminating at the level of the upper extremity of the heating flue systems, an ascension pipe opening extending through one end of the roof, a metallic coal-delivery pipe extending down through the center of the roof and also terminating at its lower end at the level of the upper extremity of the heating flue systems, and a recessed channel formed in the bottom of the roof, said channel being recessed from the base of the roof upwardly and inwardly from the two ends of the roof so as to surround

the delivery pipe to allow the gas collected in the collecting space to pass over and above the coal pile formed from the delivery pipe to the ascension pipe opening, but being shallow relative to the depth of the massive roof to confine the passing gas closely to the tops of the heating systems and thus prevent undue cooling and condensation of the gas so passing, a supply hopper with a depending outlet branch for the delivery

5 pipe, said delivery pipe being arranged for withdrawal through the roof and having a telescopic connection with the hopper outlet branch for partial withdrawal of the discharge end of the delivery pipe out of the recess up into the roof structure out of path of decarbonizing gases during decarbonization of the top of the oven chamber.

PAUL SOULARY.
